RETRACTABLE LIPSTICK HOLDER

Bernard A. Rosen, Baltimore, Md.

Application November 12, 1949, Serial No. 126,895

2 Claims. (Cl. 206—56)

1

This invention refers to the use of cosmetics and more particularly to lipstick holders.

The conventional lipstick holder operates when rotated to expel a portion of the lipstick so it may be applied to the face of the user conveniently and effectively. It requires effort to move the lipstick in and out of its shell. Lipstick has the objection of being liable to color or discolor any table cloth or surface that the holder is laid down on during the use, unless the user has gone to the trouble of rotating the holder so the lipstick is returned into it. The lipstick is hard to keep clean and sanitary by reason of this characteristic, especially if the user is forgetful of returning it into the casing. Another objection is in the fact that an open slot is left in the outer wall of the holder through which dust can enter laterally into the lipstick. In this invention, the holder is of the same general appearance as the conventional article, but has features that make it more sanitary, convenient to use and attractive. The outer wall of the holder is closed in, even though it works on the same principles as the conventional type. The lipstick is automatically returned into the holder when not in use and it uses a frictionless arrangement in its mechanism.

It is therefore an object of the present invention to provide a new and improved lipstick holder that will avoid one or more of the objections, disadvantages and limitations of the prior art.

Another object of this invention is to provide a new and improved lipstick holder that will automatically return its lipstick into the shell when not in use.

A further object of the invention is to provide a new and improved lipstick holder that will be sanitary, with its mechanism operating in a frictionless manner.

Other objects will become evident as the invention is further disclosed.

For a better understanding of the invention, its objects, its principles and the manner in which it operates, reference is made to the attached drawings. These drawings, in conjunction with the following description, outline a particular form of the invention by way of example, while the claims emphasize the scope of the invention.

In the drawings:

Figure 1 is a plan view of a lipstick holder embodying this invention, with the cap removed;

Figure 2 is a sectional view taken along line 2—2 of Figure 1 with the cap removed;

Figure 3 is a plan view showing the cap positioned on the lipstick holder;

2

Figure 4 is a side elevation of Figure 3 with parts of the cap and cylindrical shell broken away to show the slots and depressions on the outer surface of the casing;

5 Figure 5 is a view of the inner surface of the casing in flat form before rolling;

Figure 6 is a view of the outer surface of the casing shown in Figure 5;

10 Figure 7 is a view of the inner surface of the shell in flat form before rolling; and

Figure 8 is a view of the outer surface of the shell shown in Figure 7.

Similar reference numerals pertain to the same parts throughout the drawings.

15 The particular construction shown in the drawings, consists of a cylindrical cap 10 mounted over the cylindrical shell 11, forming the general external structure of a lipstick holder. The shell 11 is formed with a corrugation or groove 12 on

20 its internal surface running in a longitudinal direction in an angular or arcuate position thereon. The upper edge portion 14 of the shell is bent inwardly to reinforce it, as well as to retain a cylindrical inner casing 15 therein. The

25 casing is more or less free so it may rotate easily within the shell 11. The casing 15 has slots 16 and 17 formed on its outer surface and running oppositely to the corrugation 12. The bottom portion 18 has a flange 20 extended externally of the shell 11, as indicated in Figure 2 and is swaged in at the edge 19 to encompass the bent-over rim 21 on the bottom of the shell 11. This

30 arrangement allows the casing 15 to rotate freely in the shell 11, which can be done by holding the flange 20 between the fingers of one hand stationary while the fingers of the other hand are used to grasp the shell 11 and turn it, when the cap 10 is removed.

35 A cup 22 is loosely fitted in the casing 15 so it can reciprocate and rotate on its axis therein, and does so when the casing 15 is turned and the shell 11 held still. This is accomplished by the use of a lug 13 pressed out from the wall of the cup to fit in the slot 16 and corrugation 12, while holding a bearing ball 23. This arrangement causes the cup 22 to rise in the casing 15 when the casing is turned in the shell 11, in the customary manner. A ball 24 in a groove 25 in the cup 22 and in the slot 16 serves to guide the cup as it rotates and reciprocates in the casing, during the projection and return of the lipstick 26.

40 When the cup 22 has reached its limit of travel

outwardly, the casing 15 has rotated in the shell

45 50 55 11 so the balls 23 and 24 have travelled in the

When the cup 22 has reached its limit of travel outwardly, the casing 15 has rotated in the shell 11 so the balls 23 and 24 have travelled in the

slots 16 and 17 and corrugation 12 until they have reached their travel limit. When this limit has been reached, a clip consisting of a flat spring 27 and pin 28 mounted on the exterior wall of the shell 11 is pressed in by the finger of the user through a hole 29, into any one of a series of depressions 30 in the exterior wall surface of the casing 15. This holds the casing 15 in place and incidentally secures the cup 22 so its lipstick 26 will project in operative position. When this spring and pin are released, the cup under the tension of a helical spring 31 is pulled down to the bottom of the casing 15 and withdraws the latter with it in the shell 11. The spring 31 is fastened to the bottom 18 of the shell and tends to pull the cup inwardly. When the cup is moved towards the open end of the holder, it not only tensions the spring but also acts torsionally on it. Thus it acts to facilitate the turning of the casing back to its normal position in the shell. The lipstick 26 within the casing 15 is pulled in when the cup is pulled back. This keeps it clean, when the holder is dropped on a floor or laid on a horizontal surface. It automatically relieves the user from the trouble of returning the lipstick by hand into the shell 11 when she is not using it. The ball bearings 23 and 24 reduce friction considerably and make the holder easier to handle. The clip is recessed so that it will be out of the way of the cap when the latter is pushed on the shell. The flat spring 27 is tensioned outwardly enough to be available for contact with the finger of the user when the holder is in position to permit the use of its lipstick 26. The fact that the lipstick has to be projected by the efforts of the user, assures the user that she must get the holder ready for that purpose, and when the holder has completed its work, it will retract automatically its lipstick, into its protecting shell. The keeping of the clip in position during the use of the lipstick is done by the finger of the user in a convenient manner, by holding the holder in a normal position with the finger pressing on the clip.

Although the device is mentioned for use with lipsticks it is appreciated that it can be effectively used for any purpose where it is desired to withdraw an article into its protective casing at predetermined intervals.

The cap 10 in addition to closing the end of the device also holds the pin 28 in retracted or locked position in the depressions 30 and prevents the flange 20 from turning and raising the lipstick so its end will be crushed and pressed tightly against the inner top surface of the cap 10.

While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. A lipstick holder comprising an outer shell having an internal helical groove formed therein, a casing within the shell having a helical open slot alignable with said groove, a cup within said casing to receive a lipstick, a lug extending laterally from the outer side wall of the cup and projecting through said slot and into said groove, said lug being confined within said groove, a bottom closure integral with said casing, said closure having an upstanding flange outwardly of said shell, whereby when the closure is fixedly held the shell is rotatable about the casing and within the closure to cause rotation and translation of the cup and lipstick outwardly of the shell, the aforesaid cup being spaced from the bottom closure of the casing, a helical spring coiled in the space between the cup and the closure, said spring having its free ends secured to said cup and closure whereby, when the cup moves upwardly and rotates, it unwinds the coils of the spring, and a flexible tongue struck out and extending outwardly of the shell at its upper end, the casing having a series of depressions carried outwardly thereby opposite said tongue, the tongue being manually pressed into one of said depressions to lock the casing and shell against torsional and withdrawing pull of the spring while the lipstick is in extended position, said spring pulling the cup downwardly and assisting its rotation due to its normal winding tendency when pressure on the aforesaid tongue is released.

2. A lipstick holder as set forth in claim 1, in combination with a cover sliding over the shell and forcing the tongue into one of the depressions to automatically lock the shell and casing when the holder is not in use.
